(57) **CLAIM**

The ornamental design for a snow removal apparatus, as shown and described.

DESCRIPTION

FIG. 1 is a side elevation of the snow removal apparatus of the present invention, the broken line showing is for illustrative purposes only and forms no part of the claimed design.

FIG. 2 is a top plan view.

FIG. 3 is a rear elevation.

FIG. 4 is a side elevation looking at the opposite side from FIG. 1.

FIG. 5 is a view similar to FIG. 4 but showing the snow removal apparatus without the environment of FIG. 4.

FIG. 6 is a front elevation; and,

FIG. 7 is a bottom plan view.
